AUTOMOBILE ENGINE CARBURETOR
CHOKE VALVEMilton J. Kittler, Detroit, and Arthur G. Winter,
Pleasant Ridge, Mich., assignors to George M.
Holley and Earl Holley

Application November 6, 1948, Serial No. 58,748

5 Claims. (Cl. 261—62)

1

The object of this invention is to improve the distribution of fuel in the venturi of an automobile type engine carburetor.

Additional objects are to lower the cost of an ordinary automobile carburetor and to reduce its overall height.

We have discovered that by locating the butterfly choke valve in the throat of the venturi we reduce the overall height and thus reduce the cost. At the same time we improved distribution as the butterfly choke valve, we found, formed the very best type of fuel distributor when the fuel was discharged along the downstream side of the shaft of the butterfly choke valve.

Fig. 1 shows a cross-sectional elevation of the preferred form of our invention.

Fig. 2 shows a cross-sectional elevation on plane 2—2 of Fig. 1.

Fig. 3 shows an alternative form of the choke valve.

Fig. 4 shows a cross-sectional elevation on plane 4—4 of Fig. 3.

Fig. 5 shows still another alternative form of the choke valve and shaft.

Fig. 6 shows a cross-sectional elevation on plane 6—6 of Fig. 5.

Figs. 7 and 8 show another form of the choke valve in which inclined grooves are used.

In the Figures 1 and 2, 10 is the air entrance, 12 is the choke valve or throttle mounted on shaft 11 located in 14 which is the throat of the venturi. Grooves 17 and 18, in choke or throttle 12, are in line with the fuel outlet passage 20 which draws fuel from fuel well 22, which draws its fuel from a fuel restriction 28 (Fig. 1) connected to a float chamber 16. Air is admitted at air vent 26 down a tube 24.

A choke throttle shaft bushing 30 is cut away to form the segmental fuel outlet passage 20 in the form of a portion of an annulus.

The throttle 34 subjects the low speed fuel outlet 36 to fuel manifold engine suction. A second low speed fuel orifice 38 vents air into the outlet 36 and as the throttle 34 opens, low speed fuel also discharges from outlet 38.

The low speed fuel passage 40 connects the low speed fuel orifices 36—38 with the bottom of the main fuel well 22. An air bleed 41 is provided to break the syphon.

In Figs. 3 and 4 grooves 50, in the choke valve 52, help distribute the fuel and are located on both sides of the choke valve 52.

In Figs. 5 and 6 a slot 54, in choke throttle shaft 51, serves as a fuel outlet and increases the area of the fuel outlet 26. An automatic suc-

2

tion relief valve 58, on the downstream side of the choke valve 56, also serves to improve distribution when the choke valve is wide open. The eddy back of the valve spring draws the fuel into the middle of the air stream.

In Figs. 7 and 8 the inclined grooves 59 and 60 have also been found beneficial to improve distribution.

Operation

10 In Figs. 1 and 2 low speed operation is well known and need not be described. When the choke valve 12 is wide open as shown, fuel flows from the float chamber 16, through restriction 28 and out through the segmental passage 20 and along the grooves 17 and 18. It finally leaves the downstream lip of the choke valve 12 as a fine spray.

As it issues it is caught by the eddy created by the choke valve shaft 11 and the plate 12. The fuel is immediately atomized and distribution is thereby improved.

What we claim is:

1. A carburetor having a mixture chamber, a mixture outlet, a throttle valve in said outlet, an air entrance to said mixture chamber, a venturi in said chamber adjacent said air entrance, a butterfly choke valve and a shaft therefor arranged transversely in the throat and of said venturi, said choke valve being movable to a position to substantially completely close said venturi throat, a fuel passage through the wall of said venturi and discharging at the periphery of said choke valve so as to discharge along both sides of the downstream portion of said choke valve when said choke valve is substantially fully open and transversely of said venturi and downstream of said shaft and closely adjacent thereto.

2. A device as set forth in claim 1 in which there are grooves in said choke valve parallel to the shaft and adjacent the downstream side thereof so as to guide the fuel into the middle of the airstream.

3. A device as set forth in claim 1 in which there are grooves in said choke valves at right angles to the shaft and located downstream from the said shaft.

4. A device as set forth in claim 1 in which there is a groove in said shaft located downstream thereof and adjacent said fuel passage so as to guide fuel into the middle of the airstream.

5. A carburetor having a mixture chamber, a mixture outlet, a throttle valve in said outlet, an air entrance to said mixture chamber, a venturi

55 air entrance to said mixture chamber, a venturi

in said chamber adjacent said air entrance, a thin butterfly choke valve and a shaft therefor arranged transversely in the throat of said venturi whereby to substantially close said throat in one position of said valve, a fuel passage discharging at the periphery of said venturi downstream of and adjacent to said shaft, said passage being arranged to direct fuel along the said shaft and the downstream sides of said butterfly choke valve.
